UNITED STATES PATENT OFFICE.

JAMES F. PIERCE, OF GLYNRICH, AND HARRY A. HEINEL, OF WHITE CLAY CREEK HUNDRED, DELAWARE, ASSIGNEES TO AMERICAN VULCANIZED FIBRE CO., OF WILMINGTON, DELAWARE, A CORPORATION OF DELAWARE.

RIVETING-MACHINE.

1,301,600.

Specification of Letters Patent. Patented Apr. 22, 1919.

Application filed April 12, 1917. Serial No. 161,420.

To all whom it may concern:

Be it known that we, JAMES F. PIERCE and HARRY A. HEINEL, residing, respectively, at Glynrich and White Clay Creek Hundred, 5 in the county of New Castle and State of Delaware, have invented certain new and useful Improvements in Riveting-Machines, whereof the following is a specification, reference being had to the accompanying drawings.

Our invention relates more particularly to a work gaging and feeding mechanism for a riveting machine, wherein rivets are inserted through overlapped sections of the 15 material.

An object of our invention is to provide a work gaging and feeding mechanism, whereby the work is automatically fed and the edges to be secured uniformly overlapped 20 and held until riveted.

A further object of our invention is to provide means for shifting the work holding devices so as to position the work at predetermined points for the insertion of the 25 rivets.

These and other objects will in part be obvious, and will in part be hereinafter more fully disclosed.

In the drawings, which show by way of 30 illustration one embodiment of the invention, Figure I, is a side view of a riveting machine having the improvements applied thereto.

Fig. II, is a plan view of a portion of the 35 riveting machine and the work holding devices.

Fig. III, is a sectional view on the line III—III of Fig. I, and

Fig. IV, is a sectional view on the line 40 IV—IV of Fig. II.

Fig. V, is a sectional view on the line V—V, of Fig. I.

Our invention consists primarily in providing a riveting machine having devices 45 for placing and inserting rivets, with work holding devices which are so constructed as to clamp the overlapped edges of the material which is to be riveted and to insure that the overlapping of these edges shall be uniform throughout. To this end, we provide gaging members against which the edges of the material are placed and these gaging members hold the edges uniformly overlapped. Not only is it essential to overlap

the edges of the material uniformly but it 55 is also necessary to position the work, so that the rivets may be inserted at predetermined points. This is accomplished by constructing the work holding devices so that they may be shifted relative to the riveting mechanism and providing automatic means for shifting said work holding devices step by step through the desired distance.

Referring more in detail to the drawings, 60 a riveting machine is there shown consisting of a supporting base 1, having an overhanging arm 2, carrying a riveting head 3, in which the usual riveting devices are mounted. The rivets are automatically fed successively to the punch 3, in any well 65 known manner and as such arrangement is well known in the art, a detail illustration thereof has been omitted.

Also projecting from supporting base 1, is 70 a work supporting arm 4. This work supporting arm is in the form of a projecting bracket which facilitates the riveting of tubular articles such as baskets or the like which are preferably made of a cellulose compound ordinarily known as "fiber".

In Figs. I, and II, of the drawings a basket to be riveted is indicated at B.

The riveting tool is indicated more or less 75 diagrammatically at 5. The anvil which co-operates therewith is indicated at 6, and is supported on arm 4. Also mounted on arm 4, extending lengthwise thereof and projecting beyond the end of the arm is a supporting plate 7, which may be secured in any desirable way to arm 4. This plate 7, is 80 formed in its upper face with a dove tailed groove or recess 8.

Mounted on supporting plate 7, is a work 85 holder which consists of a lower clamping member 10, having a dove tailed projection 11, adapted to engage dove tailed recess or groove 8. This secures the work holder to supporting plate 7, but permits the same to slide endwise thereon. Lower clamping member 10, is slotted at 22, permitting anvil 6, to extend up therethrough. Co-operating 90 with the lower clamping member 10, are two clamping bars 12, and 13, each of which is provided with an ear 14, see Figs. II, and V, by means of which they are pivoted on 100 pins 44, and 45, respectively. Pins 44, and 45, are mounted in a plate 46, which is held against lower clamping member 10, under 105

yielding tension. The yielding tension is provided by means of bolts which engage plate 46, and are spring pressed against ears 48, by means of springs 49. Ears 48, are 5 formed integrally with lower clamping member 10, and project outwardly therefrom on both sides adjacent the rear end of slot 22. In this way a self adjustable pivot is formed so that clamping members 12, 10 and 13, adjust themselves to the thickness of the material being riveted.

In order to secure the free ends of bars 12, and 13 clamping devices 15, are pivoted to lower clamping member 10, and arranged 15 to coöperate with each bar. These clamping devices 15, are similar in construction and are each formed with a shank 16, which is secured to lower clamping member 10, by pivot pin 17. The shank is threaded to 20 receive nut 18, and also lock nut 19, which is extended to form a handle 20. Bars 12, and 13, are each formed with a slot 21, see Fig. II, for the reception of shank 16.

The right hand section of lower supporting member 10, as viewed in Fig. III, is raised above the left hand section so as to 25 form a gaging edge 23. The lower section of the material to be riveted is indicated at B', and contacts with this gaging edge 23. The upper section B², of the material contacts with the side edge 24, of the clamping bar 13, which in this way forms 30 a gage for the upper section of the material. These two gaging edges 23, and 24, 35 serve to secure a uniform overlapping of the meeting edges of the material to be riveted. After the sections of material have been properly placed, as stated above, bars 12, and 13, are firmly clamped against the same 40 by the nuts 18, and 19, and hold it in proper position for riveting.

Attached to the work holder at the rear end thereof is bar 25, which extends rearwardly and rests on roller 26. This bar is 45 formed on its upper face with a series of notches 27, which are adapted to be engaged by pawl 28, carried by lever 29. Spring 30, operating upon lever 29, normally moves the same to the left as viewed in Fig. I. 50 Lever 29, is adjustably connected to link 31, by means of bolt 32, which passes through slot 33, in the end of the link. The other end of link 31, is attached to a connecting rod 34, by which the riveting devices are 55 operated. Motion is imparted to connecting rod 34, by means of crank pin 35, carried by driving pulley 36, suitably supported for rotation by a bracket 37. The movements of the punch are related to those of the 60 "work feed" through this connecting link 31, so as to be alternately operative.

As the riveting tool reciprocates, lever 29, is oscillated and pawl 28, engaging notches 27, feeds or moves the work holder step by 65 step, thereby positioning the work holder

for placing the rivets at predetermined points for riveting which correspond to the notches formed in the bar 25. The predetermined position of the rivets is governed by the spacing of the teeth in the bar or jig 70 25. The work travels in the direction of the arrow shown in the drawing, and it will thus be seen that the placed rivets are in advance of the direction of motion—that is, in a direction away from the anvil. 75

It will be obvious that minor changes in the details of construction and arrangement of parts may be made without departing from the spirit of the invention as set forth in the appended claims. 80

Having thus described our invention, we claim:

1. The combination with a supporting base, of a work supporting arm projecting therefrom, an anvil supported on said arm, an overhanging arm carried by said base, a riveting head mounted on said overhanging arm and including a riveting tool with which said anvil is adapted to coöperate, a work holder for supporting and feeding the work as it is riveted including means for engaging the edges of the material to be riveted, and means for feeding and positioning the work whereby rivets are placed at predetermined points in the material. 95

2. The combination with a supporting base, of a work supporting arm projecting therefrom, an anvil supported on said arm, an overhanging arm carried by said base, a riveting head mounted on said overhanging arm and including a riveting tool with which said anvil is adapted to coöperate, a work holder for supporting and feeding the work as it is riveted including a lower supporting member, clamping bars coöperating therewith, said lower supporting member having a gaging surface for one edge of the material to be riveted, one of said clamping bars having a gaging surface for the other edge of the material to be riveted, means for holding the clamping bars for clamping the material against the lower supporting member, and means for moving the supporting member step by step. 100

3. The combination with a supporting base, of a work supporting arm projecting therefrom, an anvil supported on said arm, an overhanging arm carried by said base, a riveting head mounted on said overhanging arm and including a riveting tool with which said anvil is adapted to coöperate, a work holder for supporting and feeding the work as it is riveted including a lower supporting member, spaced clamping bars pivoted thereto and coöperating therewith, 115 said bars and lower supporting member having gaging surfaces for gaging the overlapped edge of the material to be riveted, and means for moving the work holder on the supporting member step by step, 120 125 130

whereby the material is placed into position to receive the rivets.

4. The combination with a supporting base, of a work supporting arm projecting therefrom, an anvil supported on said arm, an overhanging arm carried by said base, a riveting head mounted on said overhanging arm and including a riveting tool with which said anvil is adapted to coöperate, 5 a work holder for supporting and feeding the work as it is riveted including a slotted supporting member disposed so that said anvil is located in said slot, one of the sides of said slotted member being higher than the 10 other for forming a gaging surface, a pair of clamping bars pivoted at one end thereof to said slotted supporting member, the side of one of said clamping bars coöoperating with the high side of said slotted supporting 15 member forming gaging means for the work to be riveted, and means for moving the supporting member step by step, whereby the material is placed in position to receive the rivets.
- 20 5. In a riveting machine, the combination of a lower supporting member, clamping members coöoperating with said lower supporting member for holding the edges of the work overlapped, and means for adjusting 25 ably pivoting said clamping members to said lower supporting member, whereby the space between the clamping members and the supporting members may vary to accommodate work of different thicknesses.

6. In a riveting machine, the combination 35 of a lower supporting member, clamping members coöoperating with said lower supporting member for holding the edges of the work overlapped, means for pivoting said clamping members to said lower supporting member, and means for holding said pivot under yielding tension, whereby the 40 space between the clamping members and the supporting member varies automatically to accommodate work of different thicknesses.

7. In a riveting machine, the combination of a lower supporting member, clamping members coöoperating with said lower supporting member for holding the edges of the work 45 overlapped, ears projecting from said lower supporting member, spring pressed bolts passing through said ears, a plate engaged by said bolts, and means for pivoting said clamping members in said plate, whereby 50 the space between the clamping members and the supporting members automatically varies to accommodate work of different thicknesses.

In testimony whereof, we have hereunto 55 signed our names at Wilmington, Delaware, this fourth day of April, 1917.

JAMES F. PIERCE.
HARRY A. HEINEL.
